It is hereby certified that the assignee in Letters Patent No. 37,498, granted July 25, 1905, upon the application of Frederick Mason, of Attleboro, Massachusetts, for a "Design for a Bracelet," should have been described and specified as *Mason, Howard & Company*, instead of "Mason, Howard & Company, of Brooklyn, New York;" and that the said Letters Patents should be read with this correction therein that the same may conform to the record of the case in the Patent Office.

Signed and sealed this 15th day of August, A. D. 1905.
